COMBINATION DISH DRAINER AND
RECEPTACLE SUPPORT

Paul H. Planeta, East Hampton, Conn.

Application February 18, 1950, Serial No. 8,010

Term of patent 14 years

(Cl. D44—29)

To all whom it may concern:

Be it known that I, Paul H. Planeta, a citizen of the United States, residing at East Hampton, State of Connecticut, have invented a new, original, and ornamental Design for a Combination Dish Drainer and Receptacle Support, of which the following is a specification, reference being had to the accompanying drawing, forming a part hereof.

Fig. 1 is a perspective view of a combination dish drainer and receptacle support, showing my new design;

Fig. 2 is a top plan view; and

Fig. 3 is an end view taken from line 3—3 of Fig. 2.

I claim:

The ornamental design for a combination dish drainer and receptacle support, as shown.

PAUL H. PLANETA.
